STERN FRAME STRUCTURE

Clarence W. Allen, San Francisco, Calif.

Application February 7, 1942, Serial No. 429,888

8 Claims. (Cl. 114—57)

This invention relates to a boat structure, and especially to the stern end thereof which is designed to receive and support a propelling mechanism.

The object of the present invention is generally to improve and simplify the construction of life boats and the like, and particularly the stern end thereof; to provide a stern frame which is designed to receive and support a propelling mechanism whereby the boat is propelled, reversed and steered, and further, to provide a stern frame which receives and secures the garboard and first broad plates of the boat, and materially simplifies their attachment.

The stern structure and the propelling mechanism secured thereby is shown by way of illustration in the accompanying drawing, in which:

Figure 1 is a plan view of a life boat showing the propelling mechanism applied thereto;

Figure 2 is a central vertical longitudinal section of the rear end of the boat, said view showing the construction of the stern and also the manner in which the propelling mechanism is supported and secured;

Figure 3 is a perspective view of a portion of the stern of the boat, showing the keel, the stern frame and the manner in which the garboard and first broad plates are secured in place; and

Figure 4 is a perspective view of the type of handle applied to the push and pull rod.

Referring to the drawing in detail, and particularly Figures 1 to 3, A indicates in general a life boat, 2 the seats or thwarts extending crosswise thereof, and 3 the stern seat in the boat. The boat may be planked or built from metal, but in either instance is shaped to form a propeller recess B which is guarded by extending the keel 4 rearwardly under the recess and then upwardly to form a stern post 5. Disposed under the seat 3 is a housing generally indicated at C. Forming a support for the rear end of said housing is a bearing sleeve 6, and forming a support for the forward end of the housing is a forked standard 7 (see particularly Figure 2).

Before describing the construction of the stern in detail, it should be pointed out that the boat here shown is constructed of metal and that the stern structure in itself forms the subject matter of the present invention.

Referring to Figures 2 and 3, it will be noted that a stern frame generally indicated at D is provided. This member, while referred to as a frame, may be cast, forged, pressed or welded from plates, but whether constructed in one manner or the other there are two rear plates 8—8,

and a forwardly extending tongue 9 which is secured to the keel 4 in any suitable manner. The tongue and the plates are reenforced by a vertical rib 10. The rear end of the rib extends upwardly as shown at 11, and is welded or otherwise secured to the stern post 5. Between the plates 8 the rib is expanded to form a well 12 and an opening is formed surrounded by a seat within the well to form a support for the bearing sleeve 6. The garboard plates 14 of the boat are riveted or welded not only to the tongue 9 of the stern frame, but also to the plates 8 at the points indicated at 15 and 16. After the garboard plates have been applied, the first broad plates 14a may be applied and they are secured in place by being welded or riveted to the upper edges of the plates 8, the stern post 5 and to the upper edge of the garboard plates. This construction is important as it very materially simplifies the shaping and forming of the garboard plates, and to that extent simplifies the stern structure of the boat. This is made possible by the provision of the stern frame. The stern frame in turn reenforces and strengthens the stern structure, and at the same time, forms a support for the sleeve 6 and the housing of the propelling mechanism generally indicated at C. The bearing sleeve 6 has a flange formed on its lower end. This flange engages the seat in the well 12 and is bolted thereto as indicated at 20. Extending through the bearing sleeve and the well is the steering column 21. The lower end of the steering column is flanged as at 19 and receives and secures a torpedo-shaped housing E in which are mounted bearings to receive and support a propeller shaft which is extended through one end of the housing to carry a propeller 26.

The propelling mechanism proper is mounted within the housing C and is manually operated by a rod 61a. The rod extends forwardly in the boat and longitudinally thereof as shown in Figures 1 and 2. Bearing members 73 are placed on the seats or thwarts of the boat and the rod 40 extends through the same and is thereby held in place and guided. Upon the rod are secured sleeves 74 (see Figure 4). Each sleeve is provided with two or more handles 75 which may be grasped by the occupants of the boat to impart a push and pull motion to the rod, said motion being transmitted through the driving mechanism contained in the housing C to drive the propeller shaft.

To further brace and secure the housing C and the propelling mechanism contained therein

against the push and pull forces applied through means of the push rod 61, a brace 90 is connected to the rear end of the housing and to the upper end of the stern frame D (see Figure 2).

From the foregoing it is obvious that the boat is manually propelled by persons in the boat seated on opposite sides of the push and pull rod. For instance, a person sitting on the seat 2a may be facing the bow of the boat and will grasp the handle 75a. Another person sitting on the seat 2 and facing the stern will grasp the handle 75. Two other persons similarly seated on the other side of the rod will grasp the other two handles. Thus, four persons can apply through a sleeve 14 a push and pull force, and as three, four or more sleeves 14 may be secured to the rod, twelve, sixteen or more persons in the boat can be employed to propel the same. In a sixty-person life-boat recently tested, a speed of between five and six knots was readily maintained by sixteen men and with less effort than when rowing with oars. In fact, the speed referred to could not be obtained with oars even with a skilled crew. With the propelling mechanism here disclosed, no skill is required. In fact, any man or woman can take his or her turn.

The propelling mechanism permits propulsion, steering and reverse, and a rudder and reversing mechanism may thus be entirely eliminated. The propeller and the torpedo-shaped housing supporting the same, regardless of the position assumed, is protected by the keel 4 while in shallow water, as it is positioned between the bottom of the stern frame D and the keel. This is an important feature when beaching a boat; also the propeller and its housing being substantially under the stern and within the recess is protected from impact with other objects such as boats, wharves, etc. The stern frame D reinforces and strengthens the stern structure of the boat; it simplifies the construction; it simplifies the shaping and attachment of the garboard plates, and it forms a support and a protector for the propelling mechanism.

While these and other features of the present invention have been more or less specifically described and illustrated, I wish it understood that various changes may be resorted to within the scope of the appended claims, and that the materials and finish of the several parts employed may be such as the judgment and experience of the manufacturer may dictate or other conditions may demand.

Having thus described my invention, what I claim and desire to secure by Letters Patent is:

1. In a boat structure of the character described, a stern frame having a tongue bent to form a recess under the stern of the boat, a pair of plates at the rear end of the tongue, one on each side thereof and forming an integral part of the tongue, said plates being shaped to conform to the rear ends of the garboard plates of the boat, and a keel extending under the tongue and bent at the rear end to form a stern post, said tongue being secured at the front end to the keel and at the rear end to the stern post.

2. In a boat structure of the character described, a stern frame having a tongue bent to form a recess under the stern of the boat, a pair of plates at the rear end of the tongue, one on each side thereof and forming an integral part of the tongue, said plates being shaped to conform to the rear ends of the garboard plates of the boat, a keel extending under the tongue and bent at the rear end to form a stern post, said tongue

being secured at the front end to the keel and at the rear end to the stern post, and a vertical rib formed integral with the tongue and extending from end to end thereof, the rear end of said rib extending upwardly parallel with the stern post to reenforce the same.

3. In a boat structure of the character described, a stern frame having a tongue bent to form a recess under the stern of the boat, a pair of plates at the rear end of the tongue, one on each side thereof and forming an integral part of the tongue, said plates being shaped to conform to the rear ends of the garboard plates of the boat, a keel extending under the tongue and bent at the rear end to form a stern post, said tongue being secured at the front end to the keel and at the rear end to the stern post, a vertical rib formed integral with the tongue and extending from end to end thereof, the rear end of said rib extending upwardly parallel with the stern post to reenforce the same, said rib being expanded adjacent its rear end to form a well, and a seat formed in said well for the reception and support of a propelling mechanism.

4. In a boat structure of the character described, a stern frame having a tongue bent to form a recess under the stern of the boat, a pair of plates at the rear end of the tongue, one on each side thereof and forming an integral part of the tongue, said plates being shaped to conform to the rear ends of the garboard plates of the boat, a keel extending under the tongue and bent at the rear end to form a stern post, said tongue being secured at the front end to the keel and at the rear end to the stern post, and a pair of garboard plates secured at their rear ends to the tongue and to the rear ends of the side plates.

5. In a boat structure of the character described, a stern frame having a tongue bent to form a recess under the stern of the boat, a pair of plates at the rear end of the tongue, one on each side thereof and forming an integral part of the tongue, said plates being shaped to conform to the rear ends of the garboard plates of the boat, a keel extending under the tongue and bent at the rear end to form a stern post, said tongue being secured at the front end to the keel and at the rear end to the stern post, a pair of garboard plates secured at their rear ends to the tongue and to the rear ends of the side plates, and a pair of broad plates secured at their rear ends to the stern post and to the upper outer edges of the side plates and the garboard plates.

6. In a boat structure of the character described, a stern frame having a tongue bent to form a recess under the stern of the boat, a pair of plates at the rear end of the tongue, one on each side thereof and forming an integral part of the tongue, said plates being shaped to conform to the rear ends of the garboard plates of the boat, a keel extending under the tongue, a pair of garboard plates secured to the plates on the stern frame and to the keel, an upright extension on the rear end of the stern frame, and a pair of broad plates secured at their rear ends to said extension and along their lower edges to the side plates of the stern frame and to the garboard plates.

7. In a boat structure of the character described, a stern frame having a tongue bent to form a recess under the stern of the boat, a pair of plates at the rear end of the tongue, one on each side thereof and forming an integral part of the tongue, said plates being shaped to conform

to the rear ends of the garboard plates of the boat, a keel extending under the tongue, a pair of garboard plates secured to the plates on the stern frame and to the keel, a rib formed integral with the tongue and extending from end to end thereof, the rear end of said rib being extended substantially vertically above the plates on the stern frame, and a pair of broad plates secured at their rear ends to the vertically extended portion of the rib and along their lower edges to the side plates of the stern frame and to the garboard plates.

8. In a boat structure of the character de-

scribed, a stern frame having a tongue bent to form a recess under the stern of the boat, a pair of plates at the rear end of the tongue, one on each side thereof and forming an integral part of the tongue, said plates being shaped to conform to the rear ends of the garboard plates of the boat, a rib formed integral with the tongue and extending from end to end thereof, said rib being extended substantially vertically above the plates on the stern frame, an expanded portion in the rib to form a well, and a seat in said well.
